UNITED STATES PATENT OFFICE.

ALFRED J. FLAUDER, OF BRIDGEPORT, CONNECTICUT, ASSIGNOR TO THE WIEDLICH BROS. MFG. CO., OF BRIDGEPORT, CONNECTICUT, A CORPORATION OF CONNECTICUT.

DESIGN FOR A VASE.

Application filed July 17, 1923. Serial No. 6,793. Term of patent 7 years.

To all whom it may concern:

Be it known that I, ALFRED J. FLAUDER, a citizen of the United States, and a resident of Bridgeport, in the county of Fairfield and State of Connecticut, have invented a new, original, and ornamental Design for a Vase, of which the following is a specification, reference being had to accompanying drawing, forming a part thereof, and in which the figure is a front elevation of a vase showing my new design.

I claim:

The ornamental design for a vase substantially as shown.

Signed at Bridgeport, in the county of Fairfield and State of Connecticut, this 16th day of July, A. D. 1923.

ALFRED J. FLAUDER.
